CONTACT ASSEMBLY

Ervin E. Willis, Afton, Mo., assignor to Federal Electric Products Company, a corporation of Delaware

Application February 12, 1953, Serial No. 336,515

11 Claims. (Cl. 200—166)

The present invention relates to electric contact assemblies of the plug-in type.

Plug-in contact assemblies, of the type generally used, for example and not by way of limitation, in a draw-out switch gear, comprise a stationary blade like contact member and a companion movable plug-in contact member. The movable plug-in contact member comprises a conducting carrier element provided, at one end thereof, with a plurality of pairs of contact fingers between which the blade contact engages. Heretofore, said fingers were fixedly secured to the carrier element and were usually suitably spring biased to provide the required contact pressure, the fingers of each pair being urged apart upon engagement of the blade contact therebetween. However, the presence of corrosion or foreign matter at the point of securement or connection of the fingers to the companion carrier element tended to decrease current flow through the movable plug-in contact member.

Therefore, the primary object of the present invention is to eliminate the causes of the reduced current flow in plug-in contact members of the prior art.

Another object is the provision of a plug-in contact member wherein the contact fingers are free of fixed securement or connection to their carrier element.

Another object is the provision in a plug-in contact member of means to provide a wiping action between the contact fingers and their carrier element to provide clean contacting surfaces.

A further object is the provision of means, in a plug-in contact member provided with a plurality of pairs of contact fingers, to stagger or reduce the force required to insert the stationary contact member between the pairs of fingers or to withdraw said stationary contact member from the pairs of fingers.

The above and other objects, features and advantages of the present invention will be more fully understood from the following description considered in connection with the accompanying illustrative drawings.

In the drawings:

Fig. 1 is a perspective view of a plug-in contact assembly pursuant to the present invention, the companion movable and stationary contact members being illustrated in the disengaged condition thereof;

Fig. 2 is an exploded view, on a larger scale, of a contact finger and spring of the movable contact member;

Fig. 3 is a plan view, on a larger scale of the disengaged contact assembly, with portions broken away and sectioned for purposes of illustration;

Fig. 4 is a sectional view taken on the line 4—4 of Fig. 3, and illustrates the initial contact of the fingers of the movable contact member with the stationary contact member;

Fig. 5 is a sectional view taken on the line 5—5 of Fig. 4;

Fig. 6 is a sectional view taken on the line 6—6 of Fig. 4;

Fig. 7 is a view taken in the direction of the arrow 7 in Fig. 3, and illustrates the wiping action which occurs

during the movement of the movable contact member toward engagement with the stationary contact member;

Fig. 8 is a view similar to Fig. 7 and illustrates an intermediate position of engagement of the stationary contact member, between the contact fingers;

Fig. 9 is a view similar to Figs. 7 and 8 and illustrates full engagement of the stationary contact member between the contact fingers;

Fig. 10 is a view similar to Figs. 7, 8 and 9 and illustrates the wiping action which occurs during the movement of the movable contact member to disengage the stationary contact member;

Fig. 11 is a plan view of the movable contact member pursuant to another embodiment of the invention, parts being broken away and sectioned for purposes of illustration;

Fig. 12 is a sectional view taken on the line 12—12 of Fig. 11;

Fig. 13 is a view similar to Fig. 12, and illustrates an operative condition of engagement of the companion contacts;

Fig. 14 is a view similar to Fig. 3 and shows a modification of the movable contact member;

Fig. 15 is a sectional view taken on the line 15—15 of Fig. 14 and illustrates the initial contact of the fingers of the movable contact member with the stationary contact member;

Fig. 16 is a plan view of a movable contact member pursuant to another embodiment and modified as in Fig. 14;

Fig. 17 is a view taken in the direction of the arrow 17 in Fig. 16, and illustrates the initial engagement of a pair of contact fingers with the stationary contact member;

Fig. 18 is a view similar to Fig. 17 and illustrates the wiping action which occurs during the movement of the movable contact member toward engagement with the stationary contact member; and

Fig. 19 is a view similar to Fig. 16, showing the engaged condition of the contact assembly.

Referring now to Figs. 1 through 10 of the drawings in detail, there is illustrated a plug-in type contact assembly 20 constituted by the stationary blade-like contact member 22 and the companion movable plug-in device

24. It will be understood that the stationary contact member 22 is suitably mounted in position and the movable contact member 24 may be carried, as here shown, by a suitable portion 26 of a draw-out switch gear or similar device, being secured thereto as by the securing elements 28.

The device 24 comprises a conducting part or carrier 30 which is provided with a plurality of paired contact fingers or contact elements 32. More specifically, the contact member 24 is provided at the free end 34 thereof with a substantially rectangular frame member or cage 36 which is secured thereto as by the securing elements 49. It will be noted from Figs. 4 and 6 that the cage 36 is provided with a wall 40 thereof which extends transversely and outwardly of the marginal edge 42 of the conducting carrier 30, being preferably in abutment therewith. Said wall is provided with a plurality of longitudinally extending slots 44, there being one slot 44 for each pair of opposing contact fingers 32. The opposing wall portions 46 (Fig. 5) of the cage 36 are provided

with pairs of longitudinally aligned slots 48—48, each pair being in lateral alignment with a slot 44. Said wall portions are each provided with a flange 47, the securing elements 49 serving to secure said flanges to the carrier 30. It will be noted that there is a slot 48

70 at each side of the carrier 30. As here shown, and as presently constructed, there are four long slots 44 in wall 40, each of which accommodates a pair of opposing

contact fingers 32, and there are eight short slots 48 in the opposing wall 46, each of which accommodates a single contact finger, whereby to provide four contact fingers at each side of the carrier 30. However, it will be understood that it is within the scope of the present invention to increase or to decrease the number of pairs of contact fingers.

Pursuant to the present invention, the contact fingers 32 are mounted for limited slidable movement relative to the carrier 30.

More specifically, as best shown in Fig. 2, each contact finger 32 is provided at one side edge 54 thereof with a forward contact making portion 50 and with a rearwardly disposed contact making portion 52. Said side edge 54 is also provided with an outwardly extending portion 56 disposed intermediately of the spaced contact making portions 50 and 52 thereof. Between the portion 56 and the rear contact making portion 52, the side edge 54 is provided with an open detent recess 58. The opposing marginal edge portion 60 is also provided with an open recess 62 which constitutes a seat for a companion coiled spring 64, a stub portion 66 being provided in said seat to prevent lateral movement of the spring in the seat, the spring biasing the contact finger against the carrier.

Each contact finger 32 is mounted in the cage 36 so that it extends through a long slot 44 and an opposing short slot 48. More specifically, the forward contact portion 50 of the contact finger is disposed outwardly of the frame wall 46 and the rear contact portion 52 is disposed outwardly of the opposing frame wall 46. As will be readily apparent from Figs. 1, 4 and 7 through 10, the contact fingers 32 are paired so that there is one contact finger at each side of the carrier 30 in each of said pairs. In addition, it will be noted that the rear contact portions 52 engage the adjacent surface of the carrier 30 and that the forward contact portions 50 of each pair are in confronting spaced disposition forwardly of the forward edge 42 of the carrier. The coiled spring 64 for each contact finger 32, has one end thereof disposed over the stub 66 in the seat 62 thereof and the other end of the spring abuts the adjacent end wall 68 of the frame 36. Each slot 48 terminates adjacent the carrier member 30 in a wall portion 70 which is straddled by the previously mentioned recess 58 and serves as a detent therefor. Therefore, it will be understood, that the various fingers 32 are mounted to effect limited slidable movement of the carrier 30 relative thereto. Further, it will be understood that said movement in one direction is limited by the engagement of the side edge 76 of the recess 58 with the wall detent 70 as illustrated in Fig. 7, and said movement in the opposite direction is limited by the engagement of the opposite side edge 78 of the recess 58 with said wall detent 70, as illustrated in Fig. 10.

It will be noted that the stationary contact 22 is rounded at the free end thereof, as at 80 in order to facilitate the engagement of the stationary contact between the forward confronting contact portions 50 of the fingers 32. Adjacent the rounded end 80 thereof, the stationary contact is grooved at each side thereof, as indicated at 82, for a purpose hereinafter described in detail.

Fig. 1 illustrates the disengaged condition of the contact assembly 20. Assuming now that the movable contact member 24 is moved in a direction to engage the stationary contact 22, as indicated by the arrow 72 in Fig. 4, the rounded portion 80 of the stationary contact will initially be engaged by the confronting forward contact portions 50 of each pair of contact fingers 32, as best illustrated in said figure. In this connection, it will be understood that the space between confronting portions 50 of each pair of contact fingers is less than the thickness of the forward free end portion 80 of the stationary contact. It will also be understood that the contact fingers 32 are each disposed within the frame 26, in the disengaged condi-

tion of the contact assembly, so that each wall detent 70 abuts the edge 78 of the recess 58. Continued movement of the carrier in the same direction, after said initial engagement, results in the wiping of the carrier surfaces on the rear contact portions 52 of the various contact fingers until the opposite side edge 76 of each recess 58 is engaged by the wall detent, whereby to terminate said movement of the carrier relative to its contact fingers. Said latter position of the carrier is illustrated in Fig. 7.

It will be apparent therefore, that during the continuous movement of the carrier from the position thereof illustrated in Fig. 4 to the position thereof illustrated in Fig. 7, due to the initial engagement of the fingers with the stationary contact 22, the opposing surfaces of the carrier 30 will wipe on the contact portion 52 and on the guide portion 56 of each finger and said wiping action will tend to remove, at the contact points between the carrier and its fingers, film which may have formed on the surface of the carrier member, whether through corrosion oxidation or otherwise, and will also wipe the carrier member at said points, free of foreign material, to provide for a good electrical contact between the fingers and the carrier member. Continued movement of the movable contact device in the same direction, now results in the entry of the stationary contact between the pairs of contact fingers, as illustrated in Fig. 8. In order to effect said entry, the contact fingers yield or pivot outwardly and away from the adjacent surface of the carrier, the contact portions 52 thereof serving as fulcrums for said pivotal movement which occurs against the bias of the springs 64. Said springs are compressed upon entry of the stationary contact between the companion fingers since the stationary contact is thicker than the space between each pair of forward contact portions 50 of the fingers. The contact portions 50 ride over the edge 80 and into the adjacent groove 82 and then out of the groove and onto the surface of the stationary contact member for effecting firm mechanical and good electrical contact therewith. Fig. 9 represents the fully inserted or engaged position of the stationary contact and the movable contact device, the springs pressing the contact portions 52 against the carrier and the contact portions 50 against the stationary contact member.

In order to disengage the companion contact members, the movable contact device is withdrawn from the stationary contact member in the direction of the arrow 84 in Fig. 10.

During said withdrawal, the contact fingers move with the carrier as a unit, the contact portions 50 riding on the surfaces of the stationary contact member until they engage in the groove 82 thereof, being then in the position thereof illustrated in Fig. 8, wherein the springs bias the contact portions 50 into the groove. Continued movement of the carrier in the direction of the arrow 84 in Fig. 10, now results in a movement of the carrier relative to its contact fingers until the wall detents 70 of the cage 36 abut the marginal edges or sides 78 of the various recesses 58 in the contact fingers, as illustrated in said figure. Therefore, it will be apparent that during the movement of the carrier in the direction of the arrow 84, from the instantaneous position thereof illustrated in Fig. 8, to the instantaneous position thereof illustrated in Fig. 10, there has occurred a wiping action of the carrier surfaces against the contact portions 52 of the various contact fingers. Consequently, it will be noted that two separate wiping actions occur, the first wiping action occurring upon the engagement of the movable contact device with a stationary contact member, and the second wiping action occurring upon the disengagement of the movable contact device from the stationary contact member. It will also be noted that said second wiping action conditions the contact fingers for a repetition of the first wiping action upon the next engagement of the movable contact device with the stationary contact, as will be apparent from Figs. 10 and 4. Continued movement

in the direction of the arrow 84, now results in the pivotal or yielding movement of the various contact elements, against the bias of the springs thereof, as the rounded portion of the stationary contact passes between the confronting contact portions 50 of each pair, the various contact fingers pivoting about the contact portion 52 thereof until the contact fingers disengage the stationary contact, whereupon the springs thereof expand and the fingers resume their normal disengaged condition as illustrated in Fig. 1.

Figures 14 and 15 illustrate a modification in the construction of the movable contact device. Pursuant to said modification, the springs 64 are replaced by leaf springs 86. In order to accommodate said leaf springs, the opposing end walls 68A of the frame or cage 36A are provided with the slotted portions 88. It will be noted from Fig. 14, that two aligned slotted portions 88 are provided for each leaf spring 86. In order to mount the leaf spring in the cage 36A, the spring is provided with the confronting struck-up portions 90-90. Each struck-up portion is disposed within a slotted portion 88 of the cage 36A and abuts the inner marginal edge 92 of its companion slotted portion. It will be noted that the contact fingers 32A are not provided with the recessed portion or seat 62, as in the contact fingers 32. The opposite ends of the springs 86 extend outwardly from the cage 36A to bias the opposite ends of the contact fingers 32A toward the carrier thereof. In all other respects, the movable contact device 24A functions in the same manner as the movable contact device 24 to provide for a wiping action both upon the engagement and the disengagement of the contact assembly as previously described, Fig. 15 illustrating in broken line, movement of the carrier 30 relative to the contact fingers for the wiping action upon movement of the carrier in the direction of arrow 72.

Referring now to Figs. 11, 12 and 13 there is illustrated another embodiment of the present invention. Pursuant to the present embodiment, the force which is required to effect the engagement and the disengagement of the contact assembly is reduced. In the previously described embodiment, it was necessary to pivot or yield all of the contact elements at the same time against the bias of their respective springs in order to engage or disengage the stationary contact member between the various pairs of contact fingers. However, pursuant to the present embodiment the pairs of fingers yield in sequence upon the engagement or disengagement thereof with the stationary contact member. The movable contact device 24B of the present embodiment, differs from the movable contact device 24 of Fig. 1, in that the contact fingers 32 of the latter are all of the same longitudinal dimension, whereas the contact fingers of the present embodiment are of different longitudinal dimensions, respectively. The shortest pair of contact fingers 94 are each substantially of the same longitudinal dimension as the contact fingers 32. The pair of contact fingers 96 are each longer than the contact fingers 94. The pair of contact fingers 98 are each longer than the contact fingers 96, and the pair of contact fingers 100 are each longer than the contact fingers 98. However, it will be noted that in all other respects the contact fingers of the movable contact device 24B are substantially similar to the previously described contact fingers 32, each being provided with a coiled spring 64 and with a recess 58 as previously described. The contact fingers of the present embodiment are mounted within the cage or frame 36 in the same manner as described in connection with the plug-in device 24. It will be noted from Figs. 11 and 12, that in the disengaged condition of the contact assembly, the rear contact making portions 52 of the various contact fingers of the movable contact device 24B are in alignment, the forward contact making portions 50 thereof being in staggered relationship. It will also be understood, that in each of said contact fingers, the recessed portion 58

thereof is at the same distance from the companion contact making portion 52.

Assuming now that the contact assembly is being closed, so that the carrier 30 of the movable contact device 24B is being moved in the direction of the arrow 102 in Fig. 13 toward the stationary contact member 22, it will be apparent that the stationary contact will first be engaged by the pair of longest contact fingers 100. Upon said initial engagement and due to the continuous movement of the carrier 30 in the direction of the arrow 102, the carrier surfaces will wipe past the contact portions 52 of the contact fingers 100, in the same manner as previously described. At the termination of said wiping action, the fingers 100 will yield against the bias of their springs 64 to engage the stationary contact member 22 therebetween, in the same manner as previously described. However, as said fingers 100 begin to yield, the next pair of fingers 98 will have been carried into initial engagement with the stationary contact. Consequently, as the fingers 100 are riding over the forward portion of the stationary contact, the carrier 30 is wiping against the rear contact portions 52 of the fingers 98. At the termination of the wiping action of the fingers 98, the various fingers will be disposed substantially in the position thereof illustrated in Fig. 13. It will be noted that in said position, the longest fingers 100 have already ridden out of the grooves 82 of the stationary contact member, and are disposed on the surfaces thereof rearwardly of said grooves. Consequently, it will be apparent that up until this point, the only energy that was required was the energy necessary to yield the contact fingers 100 away from each other against the bias thereof, to ride said fingers over the end 80 of the stationary contact 22 into the grooves thereof and to ride said contact fingers 100 out of the grooves and onto the surfaces of the stationary contact member. Continued movement of the carrier 30 in the direction of the arrow 102, causes the contact fingers 98 to yield in order to ride over the rounded end of the stationary contact member 22 to the position of the contact fingers 100 in Fig. 13. During said movement of the contact fingers 98 onto the stationary contact member, the latter has engaged the next pair of contact fingers 96 to effect the wiping action of the carrier 30 relative to said contact fingers 96. As the contact fingers 96 yield to ride over the rounded end of the stationary contact member, the latter engages the last pair of contact fingers 94 and the wiping action occurs between the carrier 30 and the contact portions 52 of the contact fingers 94. At the termination of the movement of the contact device 24B for the fully engaged condition thereof with the stationary contact member, the shortest contact fingers 94 have ridden out of the grooves in the contact member 22 onto the surfaces thereof rearwardly of said groove. Therefore, it will be apparent that in effecting the full engagement of the movable contact device 24B with the stationary contact member 22, the latter is sequentially engaged by the various pairs of fingers so that the maximum force or energy required at any one time is that necessary to effect the yielding movement of only one pair of contact fingers to move the latter over the rounded portion 80 of the stationary contact 22 and onto the surfaces thereof.

In order to effect the disengagement of the movable contact device 24B from the stationary contact member, the carrier 30 is withdrawn in a direction opposite to the arrow 102. All of the contact fingers initially move as a unit with the carrier 30, until the shortest contact fingers 94 engage in the grooves of the stationary contact. This results in a wiping action of the carrier 30 against the contact portions 52 of the shortest fingers 94 and upon the termination of said wiping action, due to said continuous movement of the carrier, the fingers 94 yield away from each other to ride out of the grooves and over the rounded edge 80 to disengage the stationary contact member. As the fingers 94 are yielding to ride over the rounded edge portion 80 of the stationary con-

fact, the next pair of fingers 96 reach the grooves 82 and the wiping action occurs between said fingers 96 and the carrier 30. By this time, the fingers 94 are completely disengaged from the stationary contact 22, and as the fingers 96 yield in order to ride over the edge of the stationary contact, the succeeding pair of fingers 98 engage in the grooves 82 to effect the wiping action between the carrier and the latter. The same action is repeated with respect to the longest fingers 100 as the fingers 98 ride over the edge of the stationary contact to disengage the 10 latfer, the action being terminated when the longest fingers 100 disengage the stationary contact. From the foregoing, it will be apparent that at any one time during the movement of the movable contact device 24B to disengage the stationary contact 22, only one pair of its contact fingers are yielding. Therefore, it will be readily apparent that both upon the engagement and disengagement of the movable contact device 24B, it is necessary at any one time to supply energy or force sufficient only to yield one pair of contact fingers, whereby to materially 20 reduce the energy required at any one time to effect the yielding of the fingers, when compared with the energy required in the embodiment of Fig. 1 wherein all of the fingers yield at the same time, both upon the engagement and the disengagement of the movable contact device.

Referring now to Figs. 16, 17, 18 and 19, there is shown a modification of the previously described embodiment of Figs. 11, 12 and 13, pursuant to which the modification of Figs. 14 and 15 is incorporated in this embodiment. Pursuant to the present embodiment, the cage or frame 36A of Figs. 14 and 15 having the slotted portions 88 in the end walls 68A thereof, is utilized for mounting the leaf springs 86 which are similar to the similarly numbered springs in Figs. 14 and 15, and for mounting the shorter leaf springs 86A. It will be understood that the longer springs 86 and the shorter springs 86A are each provided with the struck-up portions 90, as illustrated in Fig. 15, for mounting the springs in the end walls 68A of the cage 36A. Pursuant to the present embodiment, an energy or force staggering effect, similar to that described in connection with Figs. 11, 12 and 13 is achieved. In the present embodiment the various contact fingers are all of the same longitudinal dimension, as best illustrated in Fig. 16, however, said fingers differ in the dimension of the recessed detent portions defined therein. It will be noted that as presently constructed, there are two pairs of the fingers 104 and two pairs of the fingers 106. The fingers 104 are provided with recesses 58 which are similar in dimension to the recesses 58 in the embodiment of Figs. 1-10. However, the fingers 106 are provided with recesses 58A which are substantially longer than the recesses 58. It will be understood that the distance between the side 78 of the short recess 58 and the contact making portion 52 of the companion finger, is the same as the distance between the similar side 78 of the longer recess 58A and the contact making portion 52 of the finger associated with the latter. Therefore, it will be apparent that in the disengaged condition of the movable contact device 24C, the sides 78 of all of the recesses on the same side of the carrier 30 are in alignment, transversely of the carrier. However, it will be noted that the opposing sides of the recesses are not in alignment. More specifically, the sides 76A of the longer recesses are disposed forwardly of the similar sides 76 of the shorter recesses. In addition, it will be noted that the longer springs 86 are associated with the fingers 104 having the shorter recesses 58, and the shorter springs 86A are associated with the fingers 106 having the longer recesses 58A.

In order to engage the movable contact device 24C with the stationary contact member, 22, said device is moved in the direction of the arrow 108 in Fig. 17. This results in the initial simultaneous engagement of all of the contact fingers with the stationary contact member 22, as illustrated in Fig. 17. Continued movement of the carrier in the same direction, results in a wiping action of all of

the contact fingers relative to the carrier. Insofar as the fingers 104 are concerned, this wiping action terminates prior to the wiping action of the fingers 106. This results from the fact that the fingers 104 have the shorter recesses 58. Consequently, when the sides 76 of the shorter recesses 58 engage the wall detents 70, as illustrated in Fig. 18, wherein the carrier 30 has moved from the position thereof illustrated in Fig. 17 toward the stationary contact member, the fingers 104 begin to yield against the bias of the springs 86 thereof to ride over the forward edge of the stationary contact member. However, as illustrated in Fig. 18, the corresponding sides 76A of the longer slots 58A in the fingers 106 have not as yet been engaged by the companion wall detents 70. Therefore, the wiping action of the carrier 30 relative to the contact portions 52 of the fingers 106 continues as the fingers 104 ride over the edge 80 and out of the groove 82 of the stationary contact onto the surfaces thereof. At about the time that the forward contact portions 50 of the fingers 104 ride out of the grooves of the stationary contact member, the detent portions 70 engage the ends 76A of the longer recesses 58A in the fingers 106. The wiping action of the carrier 30 relative to the fingers 106 now terminates and said fingers begin to yield against their companion springs to ride over the edge 80 and out of the groove 82 onto the surfaces of the stationary contact 22. Therefore, it will be apparent that it was not necessary to effect the simultaneous yielding of all of the contact fingers during the engagement of the movable contact device 24C with the stationary contact 22. The force required was that necessary to first yield the pairs of contact fingers 104, and after the latter were riding on the surfaces of the stationary contact member, force or energy was again required to yield the pairs of contact fingers 106 for effecting the engagement thereof on the surfaces of the stationary contact rearwardly of the grooves therein. It will be apparent, that upon disengagement of the movable contact device 24C, the required energy is again divided. Due to the differences in the lengths of the recess 58 and 58A, respectively, when the movable contact device 24C is fully engaged with the stationary contact 22, the contact making portions 50 of the fingers 104 will be disposed at a greater distance rearwardly of the edge 80 of the stationary contact member than will be the contact making portions 50 of the fingers 106, as illustrated in Fig. 19. Consequently, upon movement of the movable contact device in the opposite direction to disengage the fingers thereof from the stationary contact, the portions 50 of the fingers 106 will engage in the grooves 82 before the engagement of the similar portions 50 of the fingers 104 in said grooves 82. This results in a wiping action between the carrier 30 and the contact making portions 52 of the fingers 106 prior to wiping action between the similar portions 52 of the fingers 104 and the carrier 30. However, due to the relationship of the dimension of the slot 58 relative to the slot 58A, the wiping action of all of said fingers relative to the carrier 30 will terminate at substantially the same time, namely when the ends 78 of both the slots 58 and the slots 58A will be in lateral alignment at each side of the carrier 30. Thereupon, continued movement of the carrier in the same direction will effect the simultaneous disengagement of all of the fingers from the stationary contact member. In this connection, it will be noted that the various fingers are now disposed relative to the carrier 30, as in Figure 17, whereby they are in condition for a following wiping action upon movement of the movable contact device 24C in a direction to engage the stationary contact member.

While I have shown and described the preferred embodiments of my invention, it will be understood that various changes may be made in the present invention without departing from the underlying idea or principles of the invention within the scope of the appended claims.

Having thus described my invention, what I claim and desire to secure by Letters Patent is:

1. In a contact assembly having companion relatively movable contacts, one of said contacts comprising a conducting part and a part for effecting electrical connection of said conducting part and the other of said contacts, said parts having electrically contacting portions, and said parts being relatively movable in wiping relation when said contacts are brought into engagement, and said other contact having means cooperating with said electrical connecting part to condition the latter for said wiping movement.

2. In a contact assembly having companion relatively movable contacts, one of said contacts comprising a conducting part and a part for effecting electrical connection of said conducting part and the other of said contacts, said parts having electrically contacting portions, and said parts being relatively movable in wiping relation when said contacts are brought into engagement, said other contact having a portion slidably engageable by said electrical connecting part, and said last mentioned portion having means to interrupt slidable movement of said electrical connecting part thereon whereby to condition the latter for said wiping movement.

3. In an electric contact assembly, a contact device comprising a conducting carrier having a pair of opposing contact elements adapted to releasably engage a companion contact therebetween, and means providing for relative movement of said carrier and contact elements in wiping relation when said contacts are brought into engagement, and said companion contact having means cooperating with said elements to condition the latter for said wiping movement.

4. In an electric contact assembly, a contact device comprising a conducting carrier having a pair of opposing contact elements adapted to releasably engage a companion contact therebetween, and means providing for relative movement of said carrier and contact elements in wiping relation, whereby to provide for wiping action between said carrier and said elements, said means being frame means provided on said carrier for said contact elements, said frame means and said contact elements having cooperating portions for limiting said relative movement, resilient means operatively interposed between said frame and said contact elements to bias the latter toward each other, and means for causing said relative wiping movement first in one direction and then in the other during engagement and disengagement, respectively, of said other of said portions with said companion contact.

5. In an electric contact assembly, a contact device comprising a conducting carrier having a pair of opposing contact elements adapted to releasably engage a companion contact therebetween, and means providing for relative movement of said carrier and contact elements in wiping relation, whereby to provide for wiping action between said carrier and said elements, and said companion contact being a blade member engageable between said contact elements, said blade member having grooved means engageable by said contact elements upon opening and closing, respectively, of said contact assembly, whereby to condition said contact elements for wiping actions upon said opening and closing, respectively, of said contact assembly.

6. In an electric contact assembly, a contact device comprising a conducting carrier having a pair of opposing contact elements adapted to releasably engage a companion contact therebetween, and means providing for relative movement of said carrier and contact elements, whereby to provide for wiping action between said carrier and said elements, said means being frame means provided on said carrier for said contact elements, said frame means and said contact elements having cooperating portions for limiting said relative movement, said contact elements having portions projecting from opposite sides, respectively of said frame means, one of said portions being in sliding contact with said carrier and the other of

said portions being engageable with said companion contact and means for causing said relative movement first in one direction and then in the other during engagement and disengagement respectively of said other of said portions with said companion contact.

7. In a contact assembly having companion relatively movable contacts, one of said contacts comprising a conducting carrier having a pair of opposing contact elements and the other of said contacts being releasably engageable therebetween, said contact elements extending in the direction of said relative movement and being mounted on said one contact, for movement of the latter relative thereto in wiping relation therewith, whereby to provide for wiping action between said carrier and said contact elements, respectively, and said other contact having portions engageable by said contact elements upon opening and closing, respectively, of said contact assembly, whereby to condition said contact elements for wiping action upon said opening and closing, respectively, of said contact assembly.

8. In an electric contact assembly, a contact device comprising a conducting carrier having a contact element adapted to make engagement with a companion contact, said contact element being mounted for relative movement in wiping relation with its conducting carrier from a first position to a second position to thereby make wiping contact therewith, means causing said contact element to move from said first position to said second position when said element is making engagement with said companion contact and for causing said contact element to move back to said first position when being disengaged therefrom.

9. In an electric contact assembly, a contact device comprising a conducting carrier having a pair of opposing contact elements adapted to releasably engage a companion contact therebetween, said contact elements being mounted for relative rectilinear movement with respect to their conducting carrier from a first position to a second position to thereby make wiping contact therewith, means causing said contact elements to move from their said first positions to their said second positions when said elements are making engagement with said companion contact and for causing said contacts to move back to their said first positions when being disengaged therefrom.

10. In an electric contact assembly, a contact device comprising a conducting carrier having a pair of opposing contact elements adapted to releasably engage a companion contact therebetween, said contact elements being mounted for relative rectilinear movement with respect to their conducting carrier from a first position to a second position to thereby make wiping contact therewith, means causing said contact elements to move from their said first positions to their said second positions when said elements are making engagement with said companion contact and cooperating means on said companion contact for causing said contacts to move back to their said first positions when being disengaged therefrom.

11. In a contact assembly having companion relatively movable contacts, one of said contacts comprising a conducting part and a part for effecting electrical connection of said conducting part and the other of said contacts, said parts having electrically contacting portions, and said parts being relatively slidably movable for providing wiping action at said portions thereof, and said other contact having means cooperating with said electrical connecting part to condition the latter for said wiping action.
